UNITED STATES PATENT OFFICE.

WILLIAM R. FAIRCLOUGH, OF BOSTON, MASSACHUSETTS.

DESIGN FOR QUILLING FOR DRAPERIES, GARMENTS, OR SIMILAR ARTICLES.

50,834.

Specification for Design.

Patented May 29, 1917.

Application filed November 10, 1916. Serial No. 130,649. Term of patent 7 years.

To all whom it may concern:

Be it known that I, WILLIAM R. FAIRCLOUGH, a citizen of the United States, and a resident of West Roxbury, Boston, in the county of Suffolk and State of Massachusetts, have invented a new, original, and ornamental Design for Quilling for Draperies, Garments, or Similar Articles, of which the following description, in connection with the accompanying drawings, is a specification.

In the drawing, the figure is a plan of a piece of drapery showing my new design.

I claim:

The ornamental design for a quilling for draperies, garments or similar articles, as shown.

In testimony whereof, I have signed my name to this specification.

WILLIAM R. FAIRCLOUGH.
